ABSTRACT

Automobile headlamp comprising a body shell supporting a bulb assembly, and a rigid molded plastic reflector having a parabolic reflector surface, said reflector having an opening therein through which the bulb can pass freely so that the reflector is not in thermal contact with the bulb assembly, and the reflector being fixed to the body shell solely in the vicinity of said opening. Abutments are provided on the interior of the body shell for steadyng the reflector.

HEADLAMP

The present invention relates to light projectors (herein termed lamps), particularly for motor vehicles, in which a light source co-operates with a reflector having at least one reflecting surface of parabolic shape.

At present, such lamps are generally equipped with reflectors made by stamping from sheet metal. The shape stability of such reflectors is generally excellent, but it is necessary to carry out very costly polishing operations to give them a good surface finish. In addition, in the case of reflectors made up of a plurality of juxtaposed parabolic surfaces, and thus of complex shape, manufacture by stamping from sheet metal is often a cumbersome process.

For lamps of small size and low power, it has been proposed to make reflectors from a moulded thermoplastic material one face of which is made to reflect light by metal deposition, in particular by aluminium deposition. These lamps have the advantages that they can easily be made in all optically desirable shapes, however complex these may be, and of exhibiting a good surface finish.

However, such reflectors have certain inherent drawbacks. They are very sensitive to temperature variations and in particular to the heating effects transmitted by the cap of the bulb which is mounted in the reflector; when they are associated with metal parts, the expansion differences between the metal and the plastics material may lead to internal stresses and/or deformations; they have only very limited resistance to impact and they must generally be placed in an external protective casing or sheath.

That is why at present the use of plastics materials for reflectors has been limited to reflectors of small size for lamps of low power.

It is an object of the present invention to provide a lamp equipped with a reflector of a plastics material and which can be made of large size and high power.

A lamp according to the invention comprises a rigid external body, at least one light source such as a bulb mounted in an aperture in the body, and an internal reflector having at least one parabolic reflecting surface and being constituted by a rigid structure of moulded plastics material and being provided with at least one opening allowing free passage for the light source therethrough and being locally fixed to the body only in the vicinity of the said opening. Outside the small fixing area, the reflector remains free in relation to the body. The light source or bulb is mounted on the body and the reflector is not in contact with the bulb or its cap. There is thus no heat transmitting contact between the cap of the bulb and the reflector.

Although it does not support the bulb, the reflector is nevertheless positioned accurately in relation to the bulb because it is fixed to the body close to the bulb mounting.

The restriction of the fixing area of the reflector to the vicinity of the opening therein permits free differential expansion of the reflector and of the body.

The body ensures good protection for the reflector, as any impact which may be suffered by the body is not generally transmitted to the reflector because of the restriction of the fixing area.

The following description, with reference to the accompanying drawings, relates to an exemplary embodiment of the invention, showing how the invention may be carried out. In the drawings:

2

ment of the invention, showing how the invention may be carried out. In the drawings:

FIG. 1 is a sectional plan view of a lamp embodying the invention; and

FIG. 2 is a cross-section along plane II-II of FIG. 1, the bulb and bulb-holder having been removed.

The lamp 10 comprises essentially a supporting body 12, a light assembly 14, a reflector 20 and a glass or lens 24.

The body 12 is a rigid structure made, for example, of pressed sheet metal. The glass 24 is adhesively joined to a shoulder 12a formed at the front of the body 12.

Opposite the glass 24, the body is provided with a rearward protuberance or crown 13, in the centre of which a collar 13a is formed.

The light assembly 14 comprises a bulb 16 and a bulb-holder 18. The bulb-holder 18 is mounted in the collar 13a, in any suitable manner.

The reflector 20 is a rigid structure made of a plastics material, of general parabolic shape. Its internal parabolic face 22 is made to reflect light by aluminium deposition.

In its central part the reflector 20 has an opening 26 through which the bulb 16 can pass freely.

The fixing of the reflector 20 in the body is effected by means of a plurality of localized connectors 28 joining the back of the reflector 20 in the vicinity of the opening 26 to the crown 13. Preferably, as shown, each connector 28 comprises a lug 34, moulded integral with the reflector 20 and provided with a threaded bore 32, and screws 30 which enter the bores 32 and clamp the lugs 34 against the crown 13.

The body 12 may, if desired, be provided with internal projections 36 constituting abutments for steadyng the extremities of the reflector.

There is no heat-transmitting contact between the bulb 16 or its cap and the reflector 20, because of the large size of the opening 26. The fixing of the reflector 20 to the crown 13 in the vicinity of the collar 13a used for the mounting of the light assembly nevertheless ensures accurate positioning of the bulb 16 in relation to the reflector 20.

Moreover, the use of localized connectors 28 in only the area of the reflector adjacent to the opening 26 leaves the whole of the reflector 20 free in relation to the body 12 under all conditions of temperature or vibration.

Naturally, connection by means of screws is only one of several possible ways; it is possible to use rivets or other conventional mechanical fixing systems; also, the lugs 34 may be made so as to co-operate, for example by latching engagement, with fixing holes formed in the crown 13. The body 12, beyond the crown 13, may be of any desired shape, not necessarily conforming to the shape of the reflector 20.

What I claim as my invention and desire to secure by Letters Patent is:

1. An automobile vehicle headlamp, comprising a rigid external metallic body, a reflector within said body, said reflector having at least one parabolic reflecting area, and an electric bulb optically cooperating with said reflector to create a luminous beam, said body having a crown surrounding an opening, said crown and body being formed as a one piece element a bulb holder within said opening and secured to said crown, said bulb holder supporting said bulb, said re-

reflector being a rigid structure formed of molded plastic material and having a central opening in registry with the opening in said body, said bulb being of such a size so as to be capable of passing freely through said opening without contacting said reflector, and means for securing said reflector to said body only in the vicinity of said openings, said securing means comprising lugs molded integral with said reflector and abutting said crown of said body, and fasteners extending through

said crown into said lugs, and abutments projecting inwardly from said body near the free end of said reflector for steadyng said reflector.

5 2. An automobile vehicle headlamp as defined in claim 1 wherein said securing means further include screws passing through holes in said crown and entering threaded bores in said lugs.
